Primary Examiner — Jeffrey D Asch*(74) Attorney, Agent, or Firm* — NSIP Law(57) **CLAIM**

The ornamental design for a mobile terminal, as shown and described.

DESCRIPTION

FIG. 1 is a front perspective view of a mobile terminal; FIG. 2 is a front view of the mobile terminal of FIG. 1; FIG. 3 is a rear view of the mobile terminal of FIG. 1; FIG. 4 is a left-side view of the mobile terminal of FIG. 1; FIG. 5 is a right-side view of the mobile terminal of FIG. 1; FIG. 6 is a top plan view of the mobile terminal of FIG. 1; and, FIG. 7 is a bottom plan view of the mobile terminal of FIG. 1. The broken lines shown in the Figures around the outer periphery of the keypad define the bounds of the claims, while all other broken lines are directed to environment and are for illustrative purposes only; the broken lines form no part of the claimed design.
